BOAT

Theodore Carpentier, Hollywood, Calif., assignor to Los Angeles Harbor Marine Co., San Pedro, Calif., a corporation of California

Filed July 22, 1963, Ser. No. 75,926

Term of patent 14 years

(Cl. D71—1)

FIG. 1 is a top plan view of a boat, showing my new design;

FIG. 2 is a side elevational view thereof;

FIG. 3 is a front elevational view thereof;

FIG. 4 is a rear elevational view thereof;

FIGS. 5 through 12 are fragmentary profile views taken on lines 5 through 12; and

FIG. 13 is a perspective view of a portion of the uppermost deck.

The side not shown is substantially the same in appearance as the side shown.

I claim:
The ornamental design for a boat, substantially as shown and described.
